Primary Examiner — Richard E Chilcot

(57) **CLAIM**

The ornamental design for a feeding pacifier, as shown and described.

DESCRIPTION

1. Feeding pacifier

1.1 : Perspective

1.2 : Front

1.3 : Back

1.4 : Left

1.5 : Right

1.6 : Top

1.7 : Bottom

1.8 : Perspective

1.9 : Cross-sectional view taken along the dashed line AA in reproduction 1.6;

1.10 : Perspective view showing the feeding pacifier in use. The broken lines in the drawings form no part of the claimed design.

1 Claim, 10 Drawing Sheets(56)
